UNITED STATES PATENT OFFICE.

ANDREW N. BRAGG, OF PINE MEADOW, CONNECTICUT.

SNAP-HOOK.

SPECIFICATION forming part of Letters Patent No. 252,015, dated January 10, 1882.

Application filed August 30, 1881. (No model.)

To all whom it may concern:

Be it known that I, ANDREW N. BRAGG, a citizen of the United States, residing at Pine Meadow, county of Litchfield, State of Connecticut, have invented a new and useful Improvement in Snap-Hooks, of which the following is a full, clear, and exact description, reference being had to the accompanying drawings, making a part of this specification.

10 My invention relates to that class of snap-hooks which have a bolt moving back and forth in a recess in the shank of the hook, and which is held against the point of the hook by means of a spring.

15 As these snap-hooks have been heretofore constructed the shank has been cast hollow in the form of a tube, which necessarily required the use of a core in the casting, and the employment of which is always attended with difficulties and increased expense; or the shank has been cast with an open groove or recess, into which the bolt could be dropped, but which required the use of an additional piece or covering-plate to keep the bolt in place.

20 25 My improvement is intended to do away with the necessity of casting the hook-shank with a core and the use of an additional covering-plate, and also assures a more perfect operation of the bolt, and I thus produce an article which is both cheaper in construction and at the same time more perfect in its action.

In the snap-hook as devised by me the shank is cast with an open groove, thus obviating the necessity of the use of a core in its casting, and 35 on each edge of the groove are two or more lips or ears capable of being bent over the groove; and the bolt, instead of moving in the hollow groove of the shank, moves in a tube which is inserted in the shank-groove, and 40 which is held therein by the bending over of the lips or ears referred to, and by a little projection, *a*, on the bottom of the groove in front of the tube or entering a recess in the tube or equivalent device. This mode of construction obviates 45 the necessity of casting the hook with a core, and as the tube is drawn from brass, steel, or some such metal, the interior in which the bolt moves will be much smoother than can be possible with a casting, and thus the snap will 50 work more perfectly than in the snap-hook as now made.

The manner of constructing my snap-hook

is shown in the accompanying drawings, in which similar letters indicate like parts.

Figure 1 is a front view of the complete snap-hook, showing all the several parts in position, part of the inclosed tube being broken away to show the spring which holds the bolt against the end of the hook. Fig. 2 is a side view of the hook as it is cast and without the bolt and the tube in which it moves. Fig. 3 is a sectional view of the bolt-tube with the bolt and spring therein.

As will be seen from Fig. 2, the hook *A A'* is cast with a hollowed or recessed shank, *A*, 65 as indicated at *c*, and is also provided at each end of such recess with projections or ears *E E E*, Figs. 1 and 2. Into this cavity or recess *c* of the shank I place a tube, *T*, made of brass, steel, or some such metal, which tube, 70 after having been placed in the recess *c*, is held firmly in place by means of the ears *E*, which are bent down or over the recess and projection *a*, as shown in Fig. 1. No special manipulation is required in inserting the tube. It is 75 only necessary to drop it into the recess and turn down the ears *E E*, and the fastening is complete. This tube *T*, which may be drawn or rolled from a strip of brass, steel, or such metal, contains the spring *S* and bolt *B*, and 80 is provided with a slot, *t*, for part of its length, in which slides the shank of the knob *b*, by which the bolt is pressed back when the snap is unlocked. The bolt, when thrown forward by its spring, strikes against the end of the 85 hooked part *A'* and forms a complete or closed link, to retain or hold anything to which the hook is fixed, and thereby the bolt is also prevented from becoming detached from the hook.

A snap-hook such as I have described above 90 can be much more cheaply made than one in which the shank is cast with a core, and the tube being drawn or rolled will be free from all the roughness likely to be found in the cast hollow of the shank, and therefore allows the 95 spring to act and the bolt to move much more freely than they can or practically will in the snap-hooks as heretofore made. The bolt is also of the simplest form, and can be made at minimum expense. If the tube is made of brass 100 or such similar metal, the liability to rust is much less than in the snap-hooks as now made. The use of any additional piece or plate to confine the bolt in place in the recess of the shank

is also dispensed with, this being effected by simply bending over the lips or ears E after the tube and bolt has been inserted therein.

If for any reason desired, as in making small light hooks, the tube T can be dispensed with, though its use for the reasons mentioned is deemed preferable and most desirable.

What is claimed is—

1. A snap-hook having its shank formed with an open hollowed recess, with folding ears or lips E E at each end thereof, and carrying a spring-bolt, substantially as and for the purposes set forth.

2. The combination, in a snap-hook, with a recessed or hollow shank provided with lips or ears E E, as described, of an inclosed separate bolt-tube, T, and bolt B, and spring S, substantially as and for the purposes described.

3. The combination, in a snap-hook, with a recessed or hollowed shank, of a bolt-tube, T, bolt B, and spring S, substantially as and for the purposes set forth.

ANDREW N. BRAGG.
